UNITED STATES PATENT OFFICE

CHARLES GILBERT HAWLEY, OF CHICAGO, ILLINOIS, ASSIGNOR TO CENTRIFIX CORPORATION, OF CLEVELAND, OHIO, A CORPORATION OF OHIO

SMOKE CLARIFIER FOR COMBUSTION ENGINES

Application filed March 10, 1926. Serial No. 93,796.

My invention relates to means for removing oil particles and solids from the gases or smoke exhausted by internal combustion engines and the like. By so doing, the exhaust may be clarified and rendered substantially unnoticeable and in every event the usual shower of oil particles from the exhaust pipe is avoided. Such is the main purpose of the invention. A further object is to accomplish the desired results by a means or apparatus in the nature of an exhaust head that shall be attractively small and of little weight and of relatively low cost, considering the character of work performed. A further and incidental object of the invention, but quite as important as any other, is to provide a centrifugal tuyère or tuyère unit that shall be of minimum weight, maximum strength and of the highest efficiency, as required by the exacting performance demanded of an oil exhaust head, and which units each complete in itself, shall be adapted for employment singly or in multiples of any desired number, according to the volume of gas to be handled.

My invention will be readily understood on reference to the accompanying drawing, in which, Fig. 1 is a plan view of the novel receiver or exhaust head embodying the present invention, parts thereof being broken away, at different levels, the better to illustrate the internal construction; Fig. 2 is a vertical section of the exhaust head; and, Fig. 3 is an enlarged vertical section of one side or portion of a single centrifugal unit, used in and comprising a part of the invention.

As will more fully appear hereinafter, I divide the performance of the work of oil and dirt recovery or separation into a series of steps or stages; first using care to condition for easy collection the difficultly recoverable particles of oil mist and agglomerate therewith the particles of carbon; then throwing down directly a portion thereof; and finally, wringing the outgoing gases free from the remaining particles, by means of the centrifugal units before mentioned.

In the drawing, 2 represents the upper end of the exhaust pipe. Resting on the flange thereof is a cast metal bottom 3 belonging to the exhaust head and characterized by an up-

standing flange 3'. Its periphery contains a groove or shoulder 3'' that becomes the seat for the lower end of the cylindrical casing 4. The top of the casing is formed by the plate 5, or may be left open. When the plate is used it is provided with a central opening 5', larger than the incoming exhaust pipe 2; and for sake of appearance or for connection with an extended pipe, the top 5 is provided with an upstanding collar 5'' around the outlet opening 5'. A ring 6 is attached to the inner wall of the casing 4 near the top 5, and this ring supports the floor or diaphragm 7. Bolts 8, which pass through the floor and through the bottom 3, serve to fasten the casing 4 tightly on the cast bottom. The tight wall 4 and the flange 3' define an oil receiving space or a pocket 9 at the bottom of the exhaust head. A drain pipe 10 leads downward from the pocket, to keep the same clear of oil and sludge.

At such distance above the open end of the exhaust pipe as not to materially obstruct the release of the gas therefrom, but near enough to receive the certain impact of the particles of oil, and of carbon, and of water carried by the gas, I arrange the hollow circular baffle 11. Preferably this baffle is concave on the underside and is provided, not only with the internal cavity 11', but also with the rounded periphery 11''. The top of the member 11 has a central boss by which it is attached to the lower end of the small pipe 12 which hangs downward from the center of the floor 7. The upper end of said pipe is open.

According to my invention, pressure air, or if available, water under pressure, is supplied to the internal cavity 11' of the baffle 11 through a tangential connection 13. The outer end of the latter contacts the wall 4 and is joined by the pipe 14, through which the cooling medium is supplied.

Air, even at temperatures exceeding 100 degrees F. serves to cool the baffle 11 sufficiently for use with the gases from a low compression engine. For use with high compression engines and high temperature exhausts a supply of cooler air, or at any rate a larger quan-

tity of air, and if possible, a stream of water, should be used.

The air that enters through the tangential inlet 13 obviously, forcibly impacts and 5 scrubs the internal periphery of the baffle 11 and, after accepting its quota of heat therefrom, is exhausted through the pipe 12. Obviously, if water be the cooling medium employed, a return pipe should be arranged to 10 receive the hot water from the center of the baffle.

Oil vapors must be condensed before they can be caught, hence, this impacting of the vapors upon the relatively cool surface of the 15 baffle. Further, the oil vapors tend to retain their heat for a longer time than the gases proper, as they are not subject to the same law of expansion and heat loss. The difference in the nature of the oil vapors is com- 20 pensated by the action of the heat absorbing baffle and the vapors condensed thereon are displaced in the form of liquid streams and globules, some of which are discharged directly into the pocket 9, leaving only a residue 25 due to be recovered and thrown down by the hereinafter described centrifugal unit or units.

Further, the coating or accumulation of oil on the concave under side of the baffle 11, 30 makes the same into a sticky surface which, on receiving the impact of the carbon particles from the exhaust, successfully retains them and they are separated or recovered along with the oil. This is true also in the 35 action of the centrifugal unit, with the result that on emerging from the exhaust head the gases are not only substantially free of oil, but also are practically free of carbon particles and tar particles and, hence, sub- 40 stantially colorless.

On rising from the lower part of the exhaust head or receiver the partially clarified gas is intercepted and acted upon by the centrifugal appliance before the gas can 45 reach the space 15 above the floor 7. In the present instance, that floor contains six openings 16, which present an aggregate area, preferably considerably greater than the area of the exhaust pipe 2, to the end that 50 the gases shall leave the exhaust head at a lower velocity than that at which they entered the exhaust head. For each said opening 16 I provide a complete centrifugal unit C of the construction clearly depicted in Figs. 1 and 2 and detailed upon a larger scale in 55 Fig. 3.

Each centrifugal unit comprises an internally tuyèred vertical cylinder 17, a top 18, and a bottom 19, together with a central vortex breaking disk 20, attached to the center of the bottom 19, as best shown at the left hand of Figs. 1 and 2. The tuyère shown is of a peculiarly light, economical and efficient form, adapted to receive the gases through a 60 plurality of longitudinal or vertical tangen-

tial tuyères, about to be described, and to cause the gases to take on a rapid whirling motion inside of the tuyère and thus centrifugally separate the heavier particles of oil, etc., and to cause the separated liquid, however foul with carbon, to collect on the bottom 19, thence to drain into the pocket 9; while the clarified gases depart through the opening 16 at the top of the tuyère.

The cylindrical portion 17, here shown, is initially made from a thin flat sheet of metal already provided with the flanges 17' at its edges. The flat sheet is sheared upon parallel longitudinal lines to form the separate blades 17^a, and those portions are pressed or punched out so as to leave a series of blades which are at an angle to the body of the sheet. Obviously, the blade portion 17^a remain integral with the unsheared marginal portions 17^b. After being sheared and pressed, as described, the sheet is rolled into the form of a cylinder with the angular tuyère blades projecting inwardly, which causes the instruck blades to slightly overlap one another in succession. Thereby, direct radial openings are avoided, and the narrow tangential tuyères 17^c are formed, one between each pair of blades. The edges of the plate, after the cylinder is formed, are welded as a rule and the cylindrical member takes on the appearance of having been formed from a section of thin walled tubing; but, as a matter of fact, a tuyère thus characterized by inwardly extending overlapping blades cannot be formed by a mere stamping operation upon a piece 100 of tubing; at least, not without several machine operations and a prohibitive amount of pressure.

As will be seen, the flanges 17' at the top and bottom of the tuyère also extend inward and they serve to retain and properly position the cup-like bottom 19 and the ring-like top 18. Those parts are put into place before the edges of the tuyèred sheet are welded or connected, as above mentioned. Little, if any, other fastening is required for the bottom 19 as its peripheral flange 19' is held between the lower ends of the tuyère blades and the flange 17'. Preferably, the ring-like top 18 is secured either by a plurality of 110 rivets 18', or by a number of spot welds.

The body of the tuyère or unit is of greater diameter than the opening 16 in the floor 7. The central opening in the ring 18 is of the same size as the opening 16, and preferably, the unit is attached to said floor 7 by means of a flange collar or sleeve 21, the upper end of which is rolled and beaded upon the floor plate 7. Thus, the unit is rigidly and permanently attached to the remainder of the exhaust head, and cannot rattle loose. It will be noted that the marginal portion 18^a of the ring 18 is in the form of a truncated cone of low pitch, and an additional feature of the invention resides in the spacing away 125 130

of that portion of the ring from the top of the tuyère blades 17^a. Thereby, a collection groove 23 is formed at the top of the unit, into which groove the separated substances which find their way to the top of the tuyère are expelled and given an opportunity to drain down the side of the tuyère or unit.

It remains to be explained that the areas of the tuyères 17^c in the aggregate materially exceed the area of the central outlet 16 at the top of the unit. In practice, the tuyère area is about double that of said outlet. In consequence, a drop of pressure within the body of the unit is avoided and the liquids that collect at the bottom of the unit therefore freely drain from the several holes 19^a that are provided near the outer periphery of the bottom 19.

Due to surface tension the liquid tends to creep across the bottom 19 toward the center and, lest this small quantity of liquid be caught up by the vortex at that point, I employ the vortex breaking or defeating disk 20. It will be understood that the rapid rotation of the continuing body of gas within the centrifugal unit, not only insures the centrifugal separation of the heavier substances, but results in the formation of an upward moving vortex at the axis of the unit. Any substances caught therein are apt to be expelled through the central outlet at the opposite end of the unit. This is the action that is prevented by the part 20. That part is elevated upon the bottom 19, as by the central post 20'. Beneath it are a number of holes 19^b for the discharge of such liquids as reach that point.

It will now be understood that the burdened gases are subjected to an initial separation in the lower part of the head or receiver and to a subsequent and final separation within the described centrifugal unit. Considerable advantage adheres to the employment of said unit in sizes of limited diameter. The centrifugal effect is thereby relatively increased. And yet, as the gases are afforded many avenues of escape, as in other multiple relations, the drop of pressure in any one unit, if any, is the measure of the total drop of pressure through all.

Various modifications of my invention and various other uses thereof; for example, in the purification of steam and gases generally, will suggest themselves to those who are skilled in the art. Therefore, it is to be understood that my invention is not limited to the precise structure herein shown and described, nor to the particular use herein elucidated. Instead, the scope of my invention is to be ascertained from the appended claims, as read in the light of the foregoing.

Having thus described my invention, I claim as new and desire to secure by Letters Patent:—

1. The herein described improvement in

exhaust heads and receivers that comprises a casing, in combination with a floor positioned horizontally therein, an inlet below said floor, an outlet above said floor, said floor containing an intermediate outlet opening, a centrifugal separating unit suspended from said floor beneath said opening therein, and an internally cooled baffle positioned in said casing opposite said inlet, substantially as described.

2. The herein described improvement in exhaust heads and receivers that comprises a casing, in combination with a floor positioned horizontally therein, and containing a plurality of intermediate outlet openings, an inlet below said floor, a main outlet above said floor and a plurality of centrifugal separating units depending from said floor at the respective intermediate outlet openings therein.

3. The herein described improvement in exhaust heads and receivers that comprises a casing, in combination with a floor positioned horizontally therein, and containing a plurality of intermediate outlet openings, an inlet below said floor, a main outlet above said floor, a plurality of centrifugal separating units depending from said floor at the respective intermediate outlet openings therein, and an initial separating baffle positioned within said casing opposite said inlet.

4. The herein described improvement in exhaust heads and receivers that comprises a casing, in combination with a floor positioned horizontally therein, and containing a plurality of intermediate outlet openings, an inlet below said floor, a main outlet above said floor, a plurality of centrifugal separating units depending from said floor at the respective intermediate outlet openings therein, and an internally cooled baffle positioned within said casing opposite said inlet.

5. An exhaust head for internal combustion engines and the like, the exhaust gases from which contain substances that do not part with their heat as readily as the expanding gases containing them, comprising a casing having an inlet and an outlet, an internally air cooled baffle positioned within the casing opposite said inlet, means directing the air tangentially against the inner periphery of said baffle for the certain cooling of the marginal portions thereof.

In testimony whereof I have hereunto set my hand this 8th day of March, A. D. 1926.

CHARLES GILBERT HAWLEY.
